UNITED STATES PATENT OFFICE.

MAX WALTEN, OF WASHINGTON, DISTRICT OF COLUMBIA.

SKYLIGHT CONSTRUCTION.

1,299,880.

Specification of Letters Patent. Patented Apr. 8, 1919.

Application filed June 4, 1917. Serial No. 172,704.

To all whom it may concern:

Be it known that I, MAX WALTEN, a citizen of the United States, residing at Washington, in the District of Columbia, have invented certain new and useful Improvements in Skylight Construction, of which the following is a specification, reference being had therein to the accompanying drawing.

10 The present invention relates to skylights or other glazed structures, and has for its purpose to provide an improved construction which will afford the necessary cushion for the glass plates, obviate the possibility of leakage in the assembled structure notwithstanding the usual irregularities, unevenness and like defects characteristic of glass plates employed in skylight constructions, facilitate the assembly of the structure, and which will permit bodily movement of the glass plates in the assembled structure as a result of settling or expansion and contraction of said plates, and thereby relieve the plates of any breaking strain to which they would 25 otherwise be subjected.

One of the important features of the invention is the provision of an improved type of cushion for the glass plates, said cushion comprising an intermingled mass 30 of soft metal fibers, preferably lead fibers, having a rope or cylindrical formation in cross section, and commonly known in the trade as lead wool or lead fiber.

A still further and important feature of 35 this invention is to provide movable supporting members upon which the cushion of lead rope is seated whereby the glass plates which rest upon this supporting structure may be firmly held or pressed against the cushions so as to make a water tight joint 40 between the glass plates and said cushions, and at the same time allow the glass plates to have lengthwise or widthwise movement due to expansion and contraction, or for any 45 other cause, the said supports moving with the glass plates as the same expand and contract, thus relieving the glass plates of any breaking strain to which they might be subjected.

Furthermore it is the purpose of the present invention to provide a skylight which will be simple in construction, efficient in use and relatively cheap to manufacture and install.

With the above and other purposes in view the invention consists in the details of

construction and in the arrangement and combination of parts to be hereinafter described and particularly pointed out in the appended claims.

In describing the invention in detail reference will be had to the accompanying drawings wherein like characters of reference denote corresponding parts in the views, and wherein:

Figure 1 is a perspective view of a fragment of a skylight constructed in accordance with my invention,

Fig. 2 is a transverse section of the same, and

Fig. 3 is a transverse section of a modification of the invention.

Referring to the drawings, the skylight bar of my improved construction is shown, indicated generally at A, and comprises a 75 main supporting member, preferably constructed of a single sheet of metal bent centrally upon itself to form a pair of parallel spaced portions 10 between which is disposed the medial rib or beam 11 of said skylight 80 bar structure. The folded sides of said supporting member are then bent outwardly and upwardly as at 12 and 13 respectively, producing troughs 14, which are so positioned as to catch any water passing around the 85 edges of the glass plates. From the outer edges of the troughs 14 the sides of the supporting member are extended downwardly and inwardly as at 15 to a point adjacent the lower edge of the medial rib or beam 11, and 90 from this point they are bent outwardly to form horizontal portions 16, and then upwardly and outwardly inclined as at 17, thereby producing at the lower portion of the skylight bar structure troughs 18 which 95 serve to catch any water which might drip from the inner sides of the glass plates. A sheet metal strip 19 is provided as indicated, the same serving to retain the sides of the supporting member in proper spaced relation and furthermore rendering the skylight bar rigid in every respect. This strip 19 conforms to the shape of the under surface of the bottom or horizontal portions 16 and the outer inclined sides 17 of the troughs 18, 100 and is held from displacement by hemming its edges around said sides as indicated at 105 20.

Seated in each trough 14 is a movable supporting member 21 which is capable of having bodily movement between the side 110 portions 10 and 13 of said trough 14. Each movable member 21 carries a substantially

cylindrical cushion 22 which seats in a V-shaped portion of the related member 21. This member 21 may be formed in any desired shape. I preferably form each cushion 22 of an intermingled mass of lead fibers of varying lengths rolled and pressed into the desired cylindrical shape, and these cushions serve to directly support the glass plates 23, the edges of which are normally spaced from the adjacent side portions 10 of the skylight bar whereby a certain amount of bodily movement of the glass plates 23 may occur without undue strain being imparted to said plates. During such movement of the glass plates, which might occur in settling of the structure, or due to expansion or contraction of said plates, the supports 21 are capable of bodily movement in the troughs 14 in response to bodily movement of the glass plates 23 transversely of the skylight bar.

The glass plates 23 are secured against upward movement by cap B which is formed of sheet metal bent to produce parallel spaced side portions 24, downwardly diverging side portions 25, and base portions 26. The side portions 24 receive therebetween the portions 10 of the main supporting member and also the medial rib or beam 11. Suitable bolts 27 are engaged through the spaced side portions 24, portions 10, and the medial rib or beam 11 for the purpose of securing the cap in place, as will be obvious. The base portions 26 of the cap B have interlocked therewith ledge strips 28, preferably made of lead or fibrous metal, which extend beneath the portions 26 and directly engage the upper faces of the glass plates 23 to form a cushion and an air and water tight joint between the cap B and the said plates 23.

It will be noted that by providing the troughs 14 I secure an absolutely water tight structure as any moisture that might pass between the strips 28 and the glass plates 23 will be received by said troughs and carried off by the latter.

In the modification illustrated in Fig. 3 the skylight bar is shown somewhat differently constructed, the same having only a single trough 29 on each side of the bar, and furthermore formed with the stationary rests or supports 30. Upon these supports suitable cushions 31 of soft metal fibers, preferably lead fibers, are adapted to rest, which cushions serve to directly support the glass plates, and furthermore prevent any water passing around the edges of said

plates. It will be noted that the cushions not only bear against the under surface of the glass plates near their edges but also extend to a point where they engage the edges of said plates, thereby producing an effective water tight joint. In this construction, no movable supports are provided, the cushions merely resting on stationary supports, and the glass plates resting on said cushions.

While I have illustrated and described one form of carrying my invention into practice it will be obvious that various changes in the details of construction and in the arrangement of parts can be resorted to without departing from the scope of the invention as set forth in the appended claims.

I claim:

1. In a skylight or glazed structure, supports, cushions resting on said supports formed of a mass of soft metal fibers of suitable lengths arranged in intermingled relation, and glass plates resting on said cushions.

2. In a skylight or glazed structure, supports, cushions resting on said supports formed of an intermingled mass of soft metal fibers of suitable lengths, shaped into substantially the form of a cylinder, and glass plates resting on said cushions.

3. In a skylight or glazed structure, supports, cushions resting on said supports formed of a suitably shaped intermingled mass of lead fibers of varying lengths, and glass plates resting on said cushions.

4. In a skylight or glazed structure, supports, cushions resting on said supports formed of an intermingled mass of lead fibers shaped into substantially the form of a cylinder, and glass plates resting on said cushions.

5. In a skylight or glazed structure, non-cushioning supports adapted for free lateral movement, cushions resting on said supports, and glass plates resting on said cushions.

6. In a skylight or glazed structure, a supporting bar having troughs formed therein, non-cushioning supports mounted for free lateral movement in said troughs, cushions resting on said supports, and glass plates resting on said cushions.

In testimony whereof I affix my signature in presence of two witnesses.

MAX WALDEN.
